COMBINED SCREENING AND AIR SEPARA-
TION OF PULVERULENT MATERIALCharles Philip Miller, Bingley, England, assignor
to Keighley Laboratories Limited, Keighley,
England, a British companyApplication November 7, 1945, Serial No. 627,143
In Great Britain November 24, 1944

2 Claims. (Cl. 209—23)

1

This invention relates to the handling and purification of pulverulent material, as particularly exemplified by used case hardening or carburising compound such as granulated charcoal, coke or carbonaceous matter.

Extensive experience in investigating case hardening troubles has shown that one of the essentials of good quality work is the use of a uniformly graded and clean carburising medium in which to pack the apparatus being treated. As the carburising medium is used over and over again by incorporating a proportion of fresh compound to make up losses it is necessary to avoid the introduction of foreign matter into the carburising medium during handling and it is necessary to free it from dust and inert matter in order to ensure a uniform carburisation. Hitherto, handling, riddling and picking out such impurities as burnt clay from the used carburising compound have always constituted major objections to the pack carburising process and when carried out by hand are both slow and dirty and involve considerable dust nuisance.

An object of the present invention is to provide apparatus for the handling and purification of pulverulent material such as exemplified by used carburising compound by means of which the objections referred to previously are substantially eliminated.

According to the present invention apparatus for the handling and purification of pulverulent material such as used carburising compound comprises in combination, a closed chamber, an inverted conical sieve disposed within said chamber and having an outlet at its apex, a suction delivery pipe entering the chamber on one side of the conical sieve, a suction outlet pipe disposed with its only inlet opening on the same axis and in the same plane as the outlet in the apex of the inverted conical sieve and located adjacent to said outlet on the same side of the inverted conical sieve as the suction delivery pipe, and means disposed beneath the inverted conical sieve for emptying the chamber when required.

In one preferred form of the invention the inlet opening in the suction outlet pipe is provided with an adjustable shroud.

The invention will now be more particularly described by way of illustration with reference to the accompanying drawing which represents a diagrammatic sectional elevation of one particular form of apparatus.

The apparatus consists of two hoppers 1 and 2, which can be emptied by close fitting valves

3 and 4 at the bottom. A flexible pipe 5 having a free end 6 is connected tangentially at 1 to the upper end of one of the hoppers, each of which are of round cross section.

5 A close fitting inverted cone 8 of perforated material having a hole 9 at its apex is fitted inside the hopper at a point just below the entrance of the flexible pipe. A pipe 10 enters the top of the hopper and extends vertically downwards inside the hopper to a point adjacent to and but a short distance above the hole in the cone. This pipe leads to a small chamber 11 on top of the other hopper 2, and open at the bottom thereto. A second or outlet pipe 12 leads out of this chamber at a point opposite to the entry of the first pipe, and is connected to a source of suction for example a fan 13 and a dust-collector 14 if necessary. A grid or sieve 15 is placed in an inclined position across the chamber 11 so that material entering from the pipe 10 must pass through it to reach the pipe 12.

20 The action of the apparatus is as follows:

25 Suction is applied to the outlet pipe 12. Air enters the flexible pipe 5 the free end 6 of which is presented to the granulated material to be removed and cleaned. Air and the material pass up to the flexible pipe 5 and whirl round the upper portion of the first hopper 1. The solid material drops into the cone 8, and the portion 30 which does not pass through the perforations rolls down to the hole 9 in the apex. If this portion is sufficiently heavy to escape the suction at the vertical pipe it falls to the bottom of the hopper, together with the smalls and dust i. e. 35 fines which pass through the perforations. The portion of the material which is sucked up through the vertical pipe 10 i. e. larger grade material than fines and capable of further use is carried to the chamber 11. All material which 40 is too large in size to pass the inclined grid 15 is deflected by the grid into the second hopper 2. If the material is required to be graded into a number of sizes more hoppers similar to the second may be employed. The grading is effected 45 by using inclined grids of different mesh, the chamber with the finest mean grid being next to the outlet to the fan. Air and some fine dust passes through the outlet pipe to the fan.

50 The smalls and undesired heavy material are discharged from the first hopper as waste. The material in the second or subsequent hoppers is good material, and when the suction is cut off, can be removed and used. In order to adjust the air separator at the bottom of the cone in the first hopper, an adjustable sleeve 16 may be

fitted at the lower end of the vertical pipe, lowering of this sleeve increases the suction and enables heavier material to be lifted.

I declare that what I claim is:

1. Apparatus for the handling and purification of pulverulent material such as used carburing compound, comprising in combination a closed chamber, an inverted conical sieve disposed within said chamber and having an outlet at its apex, a suction delivery pipe entering the chamber on one side of the conical sieve, a suction outlet pipe disposed with its only inlet opening on the same axis and in the same plane as the outlet in the apex of the inverted conical sieve and located adjacent to said outlet on the same side of the inverted conical sieve as the suction delivery pipe and means disposed beneath the inverted conical sieve for emptying the chamber when required.

2. Apparatus for the handling and purification of pulverulent material such as used carburing compound as claimed in claim 1 in which

the inlet opening in the suction outlet pipe is provided with an adjustable shroud.

CHARLES PHILIP MILLER.
